METHOD OF GASIFYING LIQUID FUELS
Willi Brödlin, Altenbach am Bodensee, Germany
Filed May 17, 1962, Ser. No. 196,573
Claims priority, application Germany May 17, 1961
1 Claim. (Cl. 158—117.5)

My present invention relates to a method of gasifying liquid fuels, especially hydrocarbons such as oil, and to a device for carrying the method into practice.

An object of this invention is to provide a method of carrying out such gasification in a manner resulting in a readily combustible gas capable of being burned with a blue, relatively soot-free flame either in situ or at some other location to which the gas may be subsequently conveyed.

Various proposals are known for increasing the efficiency of burners utilizing a fuel oil. Thus, it has been found desirable to recirculate the combustion products of an inner flame, maintained within a burner tube, by means of bypass channels carrying the hot gases preferably in a burning state back to the origin of that flame at the aperture of a nozzle into the tube. This has been more fully disclosed in my copending application Ser. No. 834,245, filed August 17, 1959 and now abandoned, which described a variety of structures for creating such bypass channels and of which the present application is a continuation-in-part. These channels, however, must evidently be made of a highly refractory material to withstand the heat of the recirculated gases, it being therefore a more particular object of my present invention to provide an improved type of gasifying device, adapted to be used as a burner or as a gas generator, in which the need for such channels has been obviated.

In my aforementioned copending application I have already indicated, with particular reference to FIG. 4 thereof, that it is possible to create in a burner chamber a combustion-promoting turbulence through the introduction of a gas stream into the chamber. This aerodynamic creation of turbulence is the principle of my present invention and involves the injection of a high-speed stream of oxidizing gas such as air, along with a flow of liquid fuel to be atomized thereby, into a burner tube so as to produce a substantially conical spray which preferably contacts the wall of the tube near its mouth and leaves around the aperture of the injection nozzle a generally toroidal pocket in which a vortex is generated by the pressure difference existing along the tube. In contradistinction to prior proposals I have found it essential that the air/fuel mixture circulating in this vortex contain an undersupply of air, i.e. a quantity of oxygen considerably less than the stoichiometric amount required for the combustion of the fuel. Thus, there occurs in the region of the nozzle outlet a preliminary combustion which is only partial and which serves to decompose the hydrocarbons of the mixture into readily burnable components such as hydrogen and carbon monoxide. Naturally, the same conditions are realizable if pure oxygen instead of air is admitted into the tube along with the fuel stream.

In general, the understoichiometric amount of oxygen may be supplied to the precombustion zone near the nozzle outlet in a variety of ways. This includes the feeding of the oxygen (alone or as part of an air flow) to the nozzle as an atomizing fluid for the injected fuel and therefore in the same direction as the latter, the admission of supplemental air through lateral ports in cross-flow to the ignitable mixture, and/or the aspiration of atmospheric air through the burner mouth in counterflow to the fuel stream. Particularly the air in-

2

take from this latter source can be readily limited or completely shut off by near or actual contact of the base of the spray cone with the tube wall. The angle of divergence of this cone, i.e. the angle included between its generatrices and its axis, will normally run between 10° and 30°.

In most instances it will be advantageous to deliver the fuel at relatively low pressure to the nozzle aperture and to atomize it by an accompanying air or oxygen stream of high velocity, preferably ranging from at least 50 m./sec. to or beyond 500 m./sec., whose gauge pressure may lie between 0.5 and 5 atmospheres. The oxygen content of the atomizing air will normally be in the vicinity of 5% of the stoichiometric amount so that further oxygen, e.g. from secondary air, will be needed to sustain the partial combustion within the tube. The total oxygen content of the atmosphere in the tube falls short by, preferably, about 30% of the stoichiometric quantity as set forth in my copending application Ser. No. 155,373, filed November 28, 1961.

The invention will be described hereafter with greater detail, reference being made to the accompanying drawing in which:

FIG. 1 shows, in axial section, a gasifying device embodying the invention;

FIG. 2 is a view similar to FIG. 1, showing a modification;

FIG. 3 illustrates, also in axial sectional view, a further embodiment; and

FIG. 4 is a cross-sectional view taken on the line IV—IV of FIG. 3.

The burner 10 illustrated in FIG. 1 comprises a tube 11 here shown to be metallic although it is also possible, in this and other embodiments, to use a ceramic tube 35 clad with a refractory metallic sheath as particularly shown in FIG. 5. Tube 11 contracts at its upstream end 12 to hug a nozzle 13 whose outlet 14 emits an ignitable mixture in a conical spray 15 having an angle of divergence α of about 10%. It will be noted that the cone 15 contacts the inner wall of tube 11 at a location 16 just ahead of the tube mouth 17. Between this location and the upstream end 12 there is defined by the inner tube wall, the nozzle 13 and the cone 15 a generally toroidal pocket 18 into which part of the injected aerosol mist is deviated in a toroidal vortex 19 due to the pressure difference between the high-pressure region of expanding gases at the tube mouth 17 and the low-pressure region at the nozzle outlet 14. The vortex 19 is supplied with additional air through lateral ports 20 whose effective cross-section can be adjusted by means of a ring 21 axially slidable on the tube 11. The nozzle 13 may have a construction similar to that described hereinafter with reference to FIG. 3.

When the emergent spray is ignited at the tube mouth 17, the flame flashes back into the interior of the tube to set up combustion in the region of turbulence within pocket 18 whereby the vortex 19 turns into a flame. Alternately, particularly if the gaseous output of the device is to be connected to a different location for storage or utilization, such an internal flame can be produced by the use of igniter electrodes 22, 23 as shown in FIG. 2 for a modified gasifier 10a. In the latter figure, wherein the shape of the spray cone 15a from nozzle 13a remains substantially unchanged, the surrounding tube is shown composed of a frustoconical downstream section 11a welded onto a cup-shaped upstream section 12a provided with the ports 20a. The inlet area of these ports 22, as in the preceding embodiment, can be regulated by suitable means not further illustrated.

Though the device 10a shown in FIG. 2 may of

course be used as a burner in the same manner as the device 10 of FIG. 1, I have schematically illustrated at 24 a conduit for carrying off the gas produced at the mouth 17a of tube section 11a.

FIGS. 3 and 4 show a gasifier 10b with a straight cylindrical discharge tube 11b, a nozzle 13b producing a spray cone 15b, a shell 25 forming an annular housing about the upstream portion of tube 11b which is provided with the ports 20b, and a central body forming a support for the elements referred to. This body has a channel 27 through which atmospheric air may be admitted into the annular clearance between body 26 and the shell 25 by way of an entrance opening 28 in a ring 29, rotation of this ring thus enabling regulation of the air supply through ports 20b by varying the alignment between channel 27 and opening 28. A central bore 29 in body 26 accommodates a needle valve 30 whose axial position is adjustable by a knob 31 whereby the flow of fuel oil from a supply pipe 32 through bore 29 into the central orifice 33 of nozzle 13b can be selectively throttled. Air under pressure, arriving through a pipe 34, flows through a similar regulating valve 35 into a lateral passage 36 of body 26 terminating at an annular channel 37 of nozzle 13b surrounding its orifice 33. The resulting spray 15b strikes the wall of tube 11b near its mouth 17b or passes outwardly in close proximity thereto so as to create conditions of turbulence similar to those previously described. The region of impingement, if any, of the spray upon the tube wall is adjustable as the tube 11b, rotatable within its sleeve 25, is threaded secured to a boss 38 of body 26 so as to be displaceable relatively thereto in axial direction.

The gasifiers according to the invention operate in all instances substantially free from soot and without traces of glowing particles in the outer or secondary-stage flame produced thereby. This flame springs up immediately after ignition, in the cold state of the burner, and can be suitably regulated by the various adjustment means described in connection with FIGS. 1 and 3. The axial extent of the turbulence zone can be very limited, e.g. of the order of 20 mm., without interfering with the ready ignitability of the inner or first-stage flame. In those cases where the developing gas is carried off for combustion elsewhere, e.g. as illustrated in FIG. 2, it will of course be necessary to supplement it with additional air or oxygen at the combustion site to establish the stoichiometric balance.

Modifications of the specific structures described and illustrated are, of course, possible without departure from 50

the spirit and scope of the invention as defined in the appended claim.

I claim:

A method of producing a combustible gas, comprising 5 the steps of axially injecting into a generally cylindrical chamber open at one end, adjacent a closed end of said chamber, an admixture of atomized liquid hydrocarbons with a high-velocity stream of oxidizing gas with a velocity of substantially 50 to 500 meters per second and constituting on the order of 5% of the stoichiometric quantity of oxygen necessary for complete combustion of said hydrocarbons, thereby creating a spray cone diverging toward said open end at an angle of substantially 10° to 10 30°, so positioning said cone within said chamber as to 15 provide a generally toroidal pocket around the apex of said cone communicating with the remainder of said chamber over substantially its entire transverse cross-section while allowing at most a small clearance between the base of said cone and the inner chamber wall with consequent generation of a vortex of ignitable mixture from 20 said spray cone within said pocket, igniting said mixture whereby a flame is established in said vortex, admitting additional oxygen to said pocket adjacent the apex of said cone, and limiting the supply of oxygen in said chamber to substantially less than the stoichiometric quantity 25 needed for combustion of said hydrocarbons whereby a combustible gas issues from said open end, said spray cone blocking substantially completely the entrance of outside air into said chamber through said open end, said oxidizing gas being admitting into said chamber at a gauge pressure ranging between substantially 0.5 and 5 atmospheres 30 and providing with said additional oxygen an oxygen supply in said chamber limited to approximately 70% of said stoichiometric quantity.
